UNITED STATES PATENT OFFICE.

GEORGE M. WEBSTER, OF FORT DODGE, IOWA.

MATCH-BOX.

1,184,286.

Specification of Letters Patent.

Patented May 23, 1916.

Application filed January 3, 1914. Serial No. 810,218.

To all whom it may concern:

Be it known that I, GEORGE M. WEBSTER, citizen of the United States, residing at Fort Dodge, in the county of Webster and State 5 of Iowa, have invented certain new and useful Improvements in Match-Boxes, of which the following is a specification.

This invention relates to improvements in match boxes of that character adapted to 10 contain a supply of matches and provided with means for igniting or striking the matches when the same are withdrawn.

It is one of the objects of my invention to provide a containing body for the 15 matches with a discharge opening through which at least one of the matches may be withdrawn or allowed to project by gravity, it being optional with the user as to whether the match is ignited or not.

20 A further object is to provide a containing body with a discharge opening and an improved form of closure therefor by means of which, and a portion of the wall of such opening, sufficient frictional resistance to 25 withdrawing movement of the match can be imparted to the end thereof so as to ignite the inflammable material on the match head.

30 A further object consists in providing a container with a discharge opening and a deflecting portion, which may be a wall portion of the container, for normally causing the matches to seek a position whereby they will project through said opening when the 35 same is not closed.

A still further object is to provide a match box with a loosely disposed frame therein so that when the supply is nearly exhausted the frame will hold the few remaining matches in a position so clearly 40 approximately upright that even the last match will readily project through the discharge opening when the same is not closed.

45 Other features of novelty will be more fully described in connection with the accompanying drawing and will be more particularly pointed out in and by the appended claim.

In the drawing:—Figure 1 is a vertical 50 sectional view of a match box embodying one form of my invention. Fig. 2 is a sectional view on line 2—2 of Fig. 1. Fig. 3 is a bottom plan view. Fig. 4 is a perspective view of a match-supporting frame.

55 Like characters of reference designate

similar parts throughout the different figures of the drawing.

As illustrated, 1 designates a match-controlling body which is herein shown of cylindrical form with both ends open. A cap 60 or lid 2 is disposed over the normally upper end in a removable manner so that the containing body can be charged with matches. A bottom for the container is indicated at 3, and the same may be removable or not, as desired. The bottom of the container is designed to function as a deflector for the matches to deflect the same toward a discharge opening 4, which is formed in the bottom 3. The discharge 70 opening 4 is disposed in the bottom 3 at a point near one wall portion of the containing body 1 and the deflecting bottom 3 is inclined downwardly toward the wall of the container 1. As shown, the bottom 3 is 75 convex so as to project upwardly into the containing body 1 and present continuously downwardly deflecting portions extending toward the wall of the body 1 at all points.

Means is provided for normally closing 80 the discharge opening 4 and also coacting with a wall portion of the opening 4 to impart the necessary friction to the match heads in order to ignite the same. As shown, said means is in the form of a flat 85 spring strip 5 which may be pivotally connected with the bottom 3 by means of a rivet or the like 6. The strip 5 is sufficient in width and length to afford suitable friction surface whereby the strip will normally retain itself in any position to which it may be adjusted. One end of the strip 5 is extended laterally and is provided on its terminal end with a button 7 for adjustment. The strip 5 is preferably reduced 90 near its operating ends, as indicated at 8, and the opposite sides 9 thereof may serve as striking portions in connection with wall portions of the opening 4. However, the size of the reduced portion 8 is such as to 95 close the opening 4 when the closure strip 5 is in position shown in Fig. 3.

In the most improved embodiment, I loosely dispose the bottom 3 on the container 1 so that the bottom 3 can be shifted 105 with respect to the container to bring the discharge opening 4 into a position below the contents of the container adjacent the matches therein, it being understood that when the supply is partially exhausted the 110

opening 4 will usually be beneath the empty portion of the container. By moving the closure relatively to the bottom 3, the opening 4 will be uncovered so that a match can 5 project therethrough by gravity, if the container is held upright. After the match has projected through the opening 4 sufficiently to permit the user to grasp one end of the match, the closure 5 may be slightly shifted 10 so that one of the striking surfaces 9 will engage the match and force the same frictionally against the adjacent portion of the wall or opening 4. When the match is withdrawn so that the enlarged head is 15 forced between the wall of the opening 4 and the striking surface 9, sufficient friction will be imparted to ignite the head and thereby light the match.

Means is provided for normally holding 20 the matches in an upright position in the container, or in a position substantially parallel with the axis of the container 1, and as shown, such means may comprise a frame 10 which may be loosely disposed in the 25 container 1. As illustrated more particularly in Fig. 4, the frame 10 is composed of intersecting partition plates 11 having lower ends reduced toward their center, and indicated at 12, to conform to the convex 30 bottom 3. In charging the container, the

matches are disposed between the partitions so that when the supply is nearly exhausted the remaining matches will be held in a sufficiently upright position to permit of egress through the opening 4.

While I have herein shown and described one form of my invention, I do not wish to be limited thereto except for such limitations as the claim may import.

I claim:—

In a match box, a match-containing structure having an inwardly dished bottom providing a continuously deflecting portion for causing the matches to seek an outward position through said structure, said structure having a discharge opening near the outer portion thereof, means for closing said opening and coacting with a wall portion thereof for igniting a match when withdrawn through said opening, and a partition frame structure shaped to conform to the shape of said bottom acting to hold said matches in a position for projection through said opening, substantially as described.

In testimony whereof I affix my signature 55 in presence of two witnesses.

GEORGE M. WEBSTER.
